UNITED STATES PATENT OFFICE.

JOHN S. H. STONEBURNER AND CHARLES D. STONEBURNER, OF ARLINGTON, VIRGINIA.

FEED-BOX.

No. 811,592.

Specification of Letters Patent.

Patented Feb. 6, 1906.

Application filed November 2, 1904. Serial No. 231,171.

To all whom it may concern:

Be it known that we, JOHN S. H. STONEBURNER and CHARLES D. STONEBURNER, residing at Arlington, in the county of Alexandria and State of Virginia, have invented a certain new and useful Improvement in Feed-Boxes, of which the following is a full, clear, and exact description, reference being had to the accompanying drawings.

10 Our invention relates to feed-boxes, and has for its object the construction of a box which may be readily applied to a wagon, which may be folded up so as to occupy but a small space when not in use, which shall prevent the loss of any of the contents, and which shall be simple and durable.

15 The invention may be generally summarized as consisting of the combinations of elements for the purpose specified set forth in 20 the claims annexed to and forming a part of this specification.

25 Referring to the drawings, Figure 1 represents a top plan view of the box, showing the same opened, the retaining-board being folded down into the position shown in Fig. 3. Fig. 2 represents an end elevation of said box. Fig. 3 represents a detail sectional view of the front and part of the bottom of the box on the line 3 3 of Fig. 1. Fig. 4 represents an 30 end elevation with part of the end broken away, showing the box open for use. Fig. 5 represents a detail in elevation of the back part of the box, and Fig. 6 represents a sectional detail on the line 6 6 of Fig. 1.

35 The box consists of a top or cover A, a back B, ends C, and a front D. The cover is hinged to the top of the back part B by hinges a a. (See Fig. 1.) The back B may be provided with a sliding portion b near each 40 end of the same for the purpose of fitting the box to the back of a wagon, the sides of said wagon being provided with the ordinary cleats for the end-gate, the back B taking the place of the ordinary back - board of such 45 wagon. A sliding connection between the part b and the back B is provided by means of a hooked strap b', having the slots b² therein, through which and through slots b⁴ in the part b extend the bolts b³, nuts b⁵ on said 50 bolts enabling the part b to be secured in any desired position with reference to the back B. The hooks b⁶ on the end of each strap b' enable the box to be supported on the side of

the wagon or any other convenient portion thereof.

55 With the width of the members b as shown in the drawings the box may be readily applied to the front or rear end of a wagon in place of the ordinary end-board thereof, provided that the cleats for such board are at the extreme end of the body, enabling said members to be supported by the end of the floor. By merely widening the said members, so that the lower edges thereof are as low as the bottom of the box, the box may be applied to wagon-bodies the bottoms of which extend considerable beyond said cleats.

With the width of the members b as shown in the drawings the box may be readily applied to the front or rear end of a wagon in place of the ordinary end-board thereof, provided that the cleats for such board are at the extreme end of the body, enabling said members to be supported by the end of the floor. By merely widening the said members, so that the lower edges thereof are as low as the bottom of the box, the box may be applied to wagon-bodies the bottoms of which extend considerable beyond said cleats.

55 The end C and the front D are secured together and the front is hinged to the bottom part E. Folding links c c', pivoted, respectively, to the ends C and the back B and pivotally connected together at c², limit the opening movement of the box and hold the parts in position for use, as shown in Fig. 4.

70 In order to prevent the loss of any grain from the ends of the box, we provide the box at each end and interiorly of the ends C with the transverse member C'. These transverse members extend from the back of the box to the front thereof when the box is closed and are of the shape shown in Fig. 4. They fit closely against the ends C; but to prevent the parts from separating, as by warping or otherwise, to permit the escape of grain therebetween we have provided 75 means for holding these parts in contact, such means being shown more particularly in Figs. 4 and 6.

75 F designates a metal plate secured, as by screws f, to the lower end of the transverse member C'. This plate is provided with an arcuate slot, the center of curvature of such slot f² being the junction of the bottom E and the front D. A bolt G extends through the lower rear portion of the end C and 80 through the slot f², a recess f³ being formed between the plate F and the portion of the transverse member C' adjacent thereto for the reception of the head of the bolt G, whereby said bolt may travel with the lower 85 portion of the end C sliding along in said slot. A stud or elongated washer g is provided between the nut g' and the end C for a purpose to be hereinafter explained.

85 In order to cause the lowering of the front 90 of the box to raise the cover of the same, we

have connected the lower rear corner of said end with said cover by means of a link. This link is made of two sections $h\ h'$, said sections being adjustably connected by means of slots 5 and bolts extending therethrough, as shown particularly in Figs. 2 and 4. By means of this adjustable connection the link-sections $h\ h'$ may be so adjusted that the act of lowering the front of the box causes the cover to be lifted, as shown in Figs. 1 and 4, and the link connection thereafter supports said cover in its elevated position.

The length of the links and their points of connection with the cover A are such that 15 when the front of the box is dropped to its lowest position said cover is rotated on its hinges to bring the free edge thereof beyond the pivot—that is, with the free edge to the rear of the vertical line extending through 20 such pivot. By this means the front of the box when lowered not only elevates the cover, but sustains it in such elevated position. Owing to the fact that the ends and front of the box are connected, the links connect said 25 cover with the front of the box through such ends.

As will be seen by an inspection of Fig. 1, the cover of the box is a little longer than the bottom of the same, and the stud or elongated washer g separates the link-sections 30 $h\ h'$ from the links $c\ c'$ and prevents the operation of one from interfering with that of the other.

In order to prevent the grain from spilling 35 over the front of the box when the front is dropped or lowered, a retaining-board K is pivotally connected, as by hinges, (not shown,) to the front D. When the box is closed, this board is folded down flat upon 40 the front D, occupying the position shown in Fig. 3. In order to support this retaining-board in its operative position, it is provided with a brace k , hinged at one edge thereof to the board K. When the board K is turned 45 up in position to retain the grain, the brace k is turned at right angles to said board with its lower edge engaging the front D. A hook k' on said brace may then be inserted into an eye d on the board D, whereby the brace is 50 held in position to support the board K in operative relation to the front D.

A canvas lining L is provided for the bottom and front of the box, whereby the escape 55 of grain between said bottom and the front D is prevented when the former is turned up to retain the grain in place. This lining may be extended up along the back B, if desired.

The retaining-board K extends from end to end of the front of the box. In order to 60 permit the front to be folded up into closing position, the transverse members C' are rabbed or recessed at c^3 , (see Fig. 4,) such recesses or rabbets being of sufficient depth to receive the folded retaining-board and at the

same time permit the front of the box to be 65 completely closed.

If desired, a small box M may be provided at any convenient place within the feed-box for the reception of tools or lunch.

The cover may be provided with block a' , 70 having a turn-button a^2 thereon adapted to hold a saw. If desired, a partition intermediate of and similar in construction to the transverse members C' may be provided, whereby the box may be divided into separate portions. 75

While we have described our invention as adapted to be applied to the back of a wagon and take the place of the tail-board thereof, it may be substituted equally well for the 80 front board thereof. In such case the cover of the box would constitute a foot-rest for the driver.

What we claim, and desire to secure by Letters Patent, is—

85

1. A feed-box for wagons, said box having a back adapted to form an end-board of the wagon-body, and means carried by said back to enable the box to be applied to wagon-bodies of different widths, substantially as 90 described.

2. A feed-box for wagons, said box having a back adapted to form an end-board of the wagon-body, and adjustable end portions carried by said back, whereby the box may 95 be fitted to wagon-bodies of varying widths, substantially as described.

3. A feed-box for wagons, said box having a back adapted to form an end-board of the wagon-body, a sliding member at each end of 100 the back having slots therethrough, a hooked plate extending across said slots, bolts extending through said back, slots, and plate, and nuts on said bolts for clamping said plate against the sliding member, substantially as 105 described.

4. A feed-box having in combination a pivoted cover, a back, a bottom, a front and ends, said front being pivoted adjacent to the bottom of the box, and connections between 110 said front and said cover for elevating the latter by the lowering of the front, said connections being adapted to rotate said cover and bring its free edge to the rear of a vertical line extending through the pivot thereof 115 when the front is fully lowered, substantially as described.

5. A feed-box having in combination a pivoted cover, a back, a bottom, a front, and ends, said front being hinged to the bottom, and links connected to said front and said cover and adapted to rotate the cover to bring its free edge to the rear of a vertical line extending through the pivot thereof when the front is fully lowered, substantially as 120 described.

6. A feed-box having in combination a back, a pivoted cover, a front, and ends, said

125

ends being carried by the front and said front being pivoted to the bottom, links connecting the lower inner extremities of the ends and the cover and adapted to rotate the cover 5 to bring its free edge to the rear of a vertical line extending through the pivot thereof when the front is fully lowered, substantially as described.

7. A feed-box having in combination a back, a bottom, a pivoted cover, a front, and ends, said ends being carried by the front and said front being pivoted to the bottom, foldable links connecting the ends and the back of the box, and links connecting the lower inner extremities of the ends and the cover and adapted to rotate the cover to bring its free edge to the rear of a vertical line extending through the pivot thereof when the front is lowered to straighten said foldable links, substantially as described.

8. A feed-box having in combination a back, a bottom, a front, and ends, the ends being carried by the front and the front being hinged to the bottom, of transverse members 25 extending from the back of the box to the front adjacent to the ends of the same, a plate secured to each of said members, said members being recessed back of said plate and said plate having an arc-shaped slot therein, 30 a headed bolt extending through each of said ends and through said slot with the head in the recess between said plate and said member, and a nut for tightening said bolt whereby the members and ends may be kept in substantial contact, substantially as described.

9. A feed-box having in combination a back, a bottom, a front, and ends, said ends being carried by the front and said front being hinged to the bottom, a retaining-board 40 extending longitudinally of the front from end to end of the same, said board being hinged to the front of the box, whereby it may be folded up when the box is closed, and means for supporting said board in an elevated position to retain the feed in the box 45 when the front is lowered, substantially as described.

10. A feed-box having in combination, a back, a bottom, a front, and ends, said ends being carried by the front and the front being hinged to the bottom, a retaining-board carried by the front and extending from end to end of the same, said retaining-board being hinged to the front, whereby it may be folded 55 down when the box is closed, a brace for said retaining-board, said brace being hinged to said board, a hook carried by said brace and an eye carried by the front board, whereby the brace may be supported in position to 60 sustain the retaining-board in an elevated position when the front is lowered, substantially as described.

11. A feed-box having in combination a back, a bottom, a front, and ends, the ends

being secured to the front and the front being 65 hinged to the bottom, transverse members extending from the back to the front of the box when the latter is closed, said members being adjacent to the ends of the box, a retaining-board extending longitudinally of the 70 front and hinged thereto whereby it may be folded down when the box is closed, and means for sustaining said board in an elevated position, the members being provided with a recessed portion or rabbet for the 75 reception of said retaining-board when the box is closed, substantially as described.

12. A feed-box having in combination a back, a bottom, a front, and ends, the ends being carried by the front and the front being 80 hinged to the bottom, transverse members adjacent to the ends and extending from the back of the box to the front of the same when the latter is closed, a canvas lining covering the bottom and front of the box, and means 85 for retaining said members and ends in substantial contact substantially as described.

13. A feed-box having in combination a back, a bottom, a front, and ends, the ends being carried by the front and the front being 90 hinged to the bottom, transverse members adjacent to said ends and extending from the back of the box to the front of the same when the latter is closed, a retaining-board extending the length of the box and hinged to said 95 front whereby it may be folded down when the front is closed, and a canvas lining covering the bottom and front of the box and the surface of the retaining-board which folds down against said front, substantially as de- 100 scribed.

14. A feed-box having in combination a back, a bottom, a front, ends, and a cover, said cover being hinged to the upper portion of the box and said front being hinged to the 105 bottom and carrying said ends, transverse members adjacent to the ends and extending from the back to the front of the box when the latter is closed, means carried by said ends and in sliding engagement with said 110 members for holding said ends and members in contact during the opening and closing movement of the front, a link connected to said means and said cover for raising said cover when the front is lowered, said link being adapted to rotate the cover to bring its 115 free edge beyond the hinges thereof when the front is fully lowered, substantially as described.

In testimony whereof we hereunto affix 120 our signatures in the presence of two witnesses.

JOHN S. H. STONEBURNER.
CHARLES D. STONEBURNER.
